By his Atty.

UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,984, dated July 1, 1890.

Application filed April 15, 1890. Serial No. 348,115. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

15 A is the body portion, and swells out at the upper part, as at B, and is mounted with a rounded cap B, surmounting an annular band C, which cap B and band C are plain. Below the body part A is an annular band E, suitably ornamented, and below this band is a base portion F, formed to act as a continuation of the body part below the band E. Below this base part F is a band G, of the shape

shown, and terminating at the bottom in a band H, suitably ornamented, and having the portion immediately above made plain. The body part and portion F are relieved by the 25 ornamental work I and K, the upper part of the portions I being formed like leaves J, and the background is ornamented by shaded work L.

The handle is made of any suitable material.

Having now described my new design, what I claim as new, and desire to secure by Letters Patent, is—

35 The design for cane or umbrella handles, substantially as herein described and shown.

In testimony of which invention I have hereunto set my hand.

HENRY O. SCHMIDT.
